UNITED STATES PATENT OFFICE.

HARRY P. DAVIS, OF PITTSBURGH, PENNSYLVANIA, ASSIGNOR TO WESTINGHOUSE ELECTRIC & MANUFACTURING COMPANY, A CORPORATION OF PENNSYLVANIA.

HAND-GRENADE.

1,303,260.

Specification of Letters Patent. Patented May 13, 1919.

Application filed November 23, 1917. Serial No. 203,534.

To all whom it may concern:

Be it known that I, HARRY P. DAVIS, a citizen of the United States, and a resident of Pittsburgh, in the county of Allegheny and 5 State of Pennsylvania, have invented a new and useful Improvement in Hand-Grenades, of which the following is a specification.

My invention relates to hand grenades, and it has for its object to provide a safety device 10 vice for the percussion firing means usually employed in such apparatus by means of which the danger of premature explosion will be substantially eliminated.

In a copending patent application of 15 Frank Conrad and Christian Aalborg, Serial No. 194,444, filed of even date herewith and assigned to the Westinghouse Electric & Manufacturing Company, is shown and described a hand grenade embodying a percussion firing means that is adapted to be actuated when released by the shock which results from impact with any body or substance that arrests the flight of the grenade. The above-mentioned percussion firing means 20 comprises a member that is supported in unstable equilibrium when the hand grenade is thrown, the firing device being actuated to ignite the explosive charge when the member is displaced from its unstable position. Such an arrangement is extremely delicate and there is a possibility that the grenade will 25 explode prematurely when it is thrown, particularly if the thrower jerks his arm and thereby imparts a shock to it.

30 By my invention, I provide a safety device for preventing premature explosion of a hand grenade without impairing the effectiveness of the firing device.

The single figure of the accompanying 35 drawing is a transverse sectional view of a hand grenade embodying my invention.

The hand grenade comprises a casing or shell 1 that is provided with coaxial openings 2 and 3. An inwardly projecting annular flange 50 surrounds the opening 3, and a cup-shaped member 51, preferably composed of relatively light compressed metal, is supported by the flange 50 and is held within the casing 1 by a cap 7 which is in threaded engagement with the opening 2. The bottom of the member 51 is provided with a centrally located opening 52, and the opening 3 in the shell 1 is internally threaded to receive a screw plug 19 of cup shape in which is supported a detonating cartridge 20. The cartridge 20 is preferably of the centerfire type, with its firing portion located immediately below the opening 52. The upper portion of the flange 50 is provided with side openings 53 which communicate with the chamber 23 within which is located an explosive mixture 24.

40 A firing pin 54 is located within the member 51 and is provided, at its lower end, with a tapered portion 55 which is adapted to strike the firing portion of the cartridge 20 when released. A disk or plate 56 is mounted on the firing pin 54 immediately above the tapered portion 55 to be engaged by one end of helical spring 57, the other end of which 45 engages the inner end of the cap 7. The firing pin 54 is further provided with a groove 58 which is located within an eccentrically disposed recess 59 in the cap 7.

45 A hollow cylindrical weight 60 surrounds the firing pin 54 and is also partially located in the recess 59. A pin 61 projects from the wall of the recess 59 through an opening 62 that is provided in the weight 60 and engages the shoulder on the firing pin 54 that 50 is formed by the groove 58, thus maintaining the firing pin 54 in its retracted position and the spring 57 under compression. The projecting portion of the pin 61 is preferably of reduced cross section and of curved contour 55 longitudinally except at its inner end, for a purpose that will hereinafter be set forth.

50 A safety pin 37 projects into a recess 63 that is provided in the firing pin 54 and serves to hold the firing pin coaxially with 55 respect to the member 51, an expelling spring 64 being interposed between the head of the pin and the bottom of the recess 63 in which it is located. The cap 7 is provided with a laterally projecting annular flange 4 which is 60 engaged by the bent-over portion 65 of a strap 66, the other end of which is secured to a projection 43 on the casing 1, as by a cotter pin 44. When the cotter pin 44 is withdrawn, the strap 66 springs away from the 65 casing and the portion 65 is disengaged from the flange 4.

65 When the parts are assembled as described above, the firing mechanism is cocked by forcing the plate 56 upwardly, against the 70 action of the spring 57, until the end of the pin 61 engages the groove 58 in the firing pin. In this position, the member 60 is in a state of unstable equilibrium and any shock 75 that is received by the casing 1 after the pin 80

37 has been expelled, will cause such movement of the member as to release the firing pin 54.

On account of the eccentric relation of 5 the firing pin 54 and the member 60, when these parts are in locking relation, and the size and form of that portion of the pin 61 which projects into the recess 59, the relatively heavy member 60 will be tilted in 10 some one of several directions to release the firing pin when the flight of the shell is arrested by impact with any object or surface, such tilting action being effected in every instance of impact whatever may be the portion 15 of the shell that comes in engagement with a body or surface.

The above described parts form no part of the present invention but are fully described and claimed in the above-mentioned 20 copending application. I will now proceed to describe my invention with relation to the above described parts, although it is to be understood that it may be as readily applied to other similar firing mechanisms for 25 hand grenades.

It will be noted that the recess 63 in the firing pin 54 is of greater diameter than the hole 67 in the cap 7. A ball 68 is located in the recess 63 and a spring 69 is interposed 30 between it and the bottom of the recess 63. So long as the safety pin 37 is held in position, the ball 68 is located near the bottom of the recess 63 but, when the safety pin is withdrawn, the spring 69 will force the ball 35 68 outwardly and maintain it partially within each of the recess 63 and the hole 67. In this position, the ball 68 may be displaced only by a distinct shock and not by any gyroscopic motion such as might be imparted to 40 the hand grenade as it leaves the hand of the thrower. The factor of safety against such premature explosions of the grenade as might be caused by displacement of the firing pin during the flight of the grenade is 45 thus materially increased. The employment of the ball 68 in no wise decreases the effectiveness of the firing mechanism, but only renders it less sensitive to slight shocks which it might receive prior to, or during, 50 its flight.

While I have shown my invention in a simple and preferred form as applied to a particular type of firing mechanism for hand grenades, it is not so limited but is 55 susceptible of various modifications within the scope of the appended claims.

I claim as my invention:

1. In a hand grenade, the combination with a spring-actuated firing device, a member 60 for releasing said firing device that is

supported in unstable equilibrium, and 65 means for locking said firing device in a safety position, of means for maintaining said firing device in its safety position against the action of said member after the said locking means is removed and until the 70 flight of the grenade is arrested.

2. In a hand grenade, the combination with a spring-actuated firing device, a member 75 for releasing said firing device that is supported in unstable equilibrium, and a spring-actuated pin for normally locking said firing device in a safety position, of means for maintaining said firing device in its safety position against the action of said member after the locking pin is withdrawn 80 and until the flight of the grenade is arrested.

3. In a hand grenade, the combination with a spring-actuated firing device, a member 85 for releasing said firing device that is supported in unstable equilibrium, and a spring-actuated pin for normally locking said firing device in a safety position, a spring-actuated ball for maintaining said firing device in its safety position against 90 the action of said member after the locking pin is withdrawn and until the flight of said grenade is arrested.

4. In a hand grenade, the combination 95 with a casing, a spring-actuated firing device located within said casing, a member for releasing said firing device that is supported in unstable equilibrium, and a spring-actuated pin for normally locking said firing device in a safety position, of a spring-actuated ball adapted to be maintained between 100 said firing device and said casing for holding said firing device in its safety position against the action of said member after the locking pin is withdrawn and until the 105 flight of said grenade is arrested.

5. In a hand grenade, the combination with a casing, a spring-actuated firing device located within said casing and provided with means for maintaining its actuating 110 spring under compression, a member for releasing said firing device that is supported in unstable equilibrium, and a spring-actuated pin for normally maintaining said firing device in a safety position, of a spring-actuated ball adapted to be forced between 115 said firing device and said casing for maintaining said device in its safety position against the action of said member when said spring-actuated pin is withdrawn. 120

In testimony whereof, I have hereunto subscribed my name this 9th day of Nov. 1917.

HARRY P. DAVIS.
